UNITED STATES PATENT OFFICE.

JOSEPH WISNIEWSKI, OF ATTLEBORO, MASSACHUSETTS.

DESIGN FOR A PLAQUE, EMBLEM, OR SIMILAR ARTICLE.

54,344.

Specification for Design.

Patented Dec. 23, 1919.

Application filed December 16, 1918. Serial No. 267,060. Term of patent 7 years.

To all whom it may concern:

Be it known that I, JOSEPH WISNIEWSKI, a citizen of Poland, residing at Attleboro, in the county of Bristol and State of Massachusetts, have invented a new, original, and ornamental Design for a Plaque, Emblem, or Similar Article, of which the following is a specification, reference being had to the accompanying drawings, forming part thereof.

In the drawings showing my new design for plaque, emblem, or similar article,

Figure 1 is a front elevation thereof, Fig. 2 is a side view of the same, and Figs. 3 and 4 are sectional views taken upon lines III—III and IV—IV, respectively, of Fig. 1.

I claim:

The ornamental design for a plaque, emblem, or similar article, as shown.

JOSEPH WISNIEWSKI.
